C. F. MURRAY.
KNUCKLE PIN RETAINER,
APPLICATION FILED AUG. 16, 1909.

974,509.

Patented Nov. 1, 1910.

UNITED STATES PATENT OFFICE.

CHARLES F. MURRAY, OF CHICAGO, ILLINOIS, ASSIGNOR TO AMERICAN STEEL FOUNDRIES, OF NEW YORK, N. Y., A CORPORATION OF NEW JERSEY.

KNUCKLE-PIN RETAINER.

974,509.

Specification of Letters Patent.

Patented Nov. 1, 1910.

Application filed August 16, 1909. Serial No. 513,032.

To all whom it may concern:

Be it known that I, CHARLES F. MURRAY, a citizen of the United States, residing at Chicago, in the county of Cook and State of Illinois, have invented certain new and useful Improvements in Knuckle-Pin Retainers, of which the following is a specification.

My present invention pertains to improvements in railway car couplers, and more particularly and especially to means associated with the pivot-pin of the coupler-knuckle to maintain the pin in place and prevent its falling out if by accident the pin becomes broken, whereby the cars will remain coupled together and in operative engagement, such retainer or support for the broken pin, however, acting also as an indicator to show that the pin has been damaged and should be replaced. In passenger cars, where the platforms or bumping devices overhang the couplers, preventing removal of the knuckle pivot-pins upwardly from the coupler, it has been customary and usual to support and maintain such pins in place by suitable means located at the bottom or under side of the coupler, and it is to be noted that my improved pin-retaining device may be readily employed for this purpose, and under such circumstances it acts at all times as a support and retainer for the pin; whereas when the appliance is employed in connection with the pivot-pins of freight car couplers, the retainer is normally inoperative and merely acts as a safeguard and indicator for a broken pin.

This invention is susceptible of a considerable variety of embodiments, and in order that a full and complete understanding of the invention may be had, I have illustrated three such embodiments on the accompanying sheet of drawings forming a part of this specification, and to which reference should be made.

In this drawing,—Figure 1 is a side elevation of a car-coupler partly broken away, and indicating one form of my improved retainers for the knuckle pivot-pin; Fig. 2 is a face view, on an enlarged scale, of the retainer and a fragment of the lower portion of the coupler proper, this figure indicating in dotted lines how the retainer may be manipulated so as to carry it away from beneath the pivot-pin to permit withdrawal of the broken parts of the latter; Fig. 3 is a fragmentary elevation, part of which is sec-

tioned, of the lower portion of a car-coupler, indicating a modified form or style of pin-retainer; Fig. 4 is a view similar to Fig. 2, of the modified style of retainer shown in Fig. 3; Fig. 5 is a view similar to Fig. 3, illustrating a further modification of the retainer; and Fig. 6 is a face view of the same, such view being similar to those of Figs. 2 and 4.

Referring to this drawing, it will be noticed that in Fig. 1, I have illustrated a car-coupler 10 of the usual type, equipped or supplied with a turning knuckle 11 pivoted on a pivot-pin 12 passing through aligned holes 13, 14 of the usual outstanding spaced arms 15 and 16. This coupler is illustrated as applied to a freight car, in which the car-body does not overhang the pivot-pin, and consequently such pin 12 has at its top end a head 17, the pin at its lower end having passed therethrough beneath the arm 15 a transverse cotter pin 18, which acts by cooperation with the arm 15 to prevent riding or working up of the pin. If no retainer for such a pin were employed and the latter became broken, the lower portions of the same would fall out, rendering the coupler inoperative and useless in many cases, and it is the object of this invention to provide a combined pin-retainer and indicator, to hold the broken portions of the pin in place and maintain the coupler in operative condition, and at the same time indicate that the concealed pin has been broken and damaged.

In the particular embodiment of this retainer illustrated in Figs. 1 and 2, the coupler 10 has integral therewith a lug 19 projecting downwardly from the bottom surface of the coupler and adjacent to the knuckle pivot-pin, as is clearly indicated. This lug 19 has a hole or aperture 20 extended therethrough, the lower portion 21 of which is of angular shape, while the upper portion 22 is of larger circular form. The retainer proper consists of a member 23 having at its lower end a foot or step 24 normally underlying the lower end of the pivot-pin 12, as is indicated in Fig. 1. Near the top end of the main body 23 of this retainer, there projects in a direction opposite to the foot or step 22 a shank or pin 25 square or angular in cross section and provided with a transversely-arranged retaining cotter-pin 26. The cross section of this shank 25 corresponds substantially in shape and size to the

portion 21 of the hole or aperture 20, so that when the retainer is in the lowered position indicated in full lines in Fig. 1, this shank fits in the part 21 of the aperture, preventing the retainer from being turned or swung upwardly. As will be readily understood, its weight normally maintains it in this position. If for any reason the pin becomes broken so that the lower portion of the same 10 descends, it will strike the foot or step 24 and rest thereon, being held thereby in operative relation with respect to the other parts of the coupler, and especially the knuckle, so that the cars will not become 15 inadvertently uncoupled or disconnected. When the pin is in this position it serves as an indicator to show that it is broken and should be replaced by a new pin.

In case it is desired to remove the pivot-20 pin or take out any broken fragment thereof, it is merely necessary to lift the pin-retainer 23 into the dotted-line position shown in Fig. 1, so that the shank 25 will reside in the round portion 22 of the aperture 20, and 25 when the retainer is in such position it may be turned into the dotted-line position shown in Fig. 2, permitting the pivot-pin to be struck blows from beneath to effect its removal, or permitting the withdrawal downwardly of any broken parts of the same. 30 This turning of the retainer is permitted, as will be obvious, by the fact that the section or portion 22 of the aperture is of sufficient size to permit turning of the angular shank 35 25. The retainer, as will be apparent, may be readily swung and dropped back into operative position when desired. The pin 12 and the cotter 26, or either alone, may be used for preventing the disengagement of 40 the retainer from its supporting lug 19 by the passage of the shank 25 out of the hole 20, the pin 12 overlapping the retainer slightly when in the lowered operative position shown. The retainer is ordinarily prevented from 45 being lifted into turning position by the lower end of the pin 12 engaging or overlapping the step 24, both of which have flat surfaces, and in such case it is necessary to push the pin 12 up somewhat before the retainer can be raised sufficiently to accomplish its turning.

In Figs. 3 and 4, a device for accomplishing practically the same result is shown, although the construction and operation are 55 somewhat different. In this case, a lug 27 is cast on the bottom of the coupler and is supplied with a square or other angular or similar hole 28 extended therethrough, this lug, as in the previous instance, being adjacent the lower end of the knuckle pivot-pin 12. In this instance the retainer 29, as in the previous case, has an outstanding foot or step 30 adapted to act as an indicator and support for the broken pin of a 60 freight car, or to act as a direct and normal

support for the knuckle-pin of a passenger-car coupler. At its top end the retainer 29 is supplied with an oppositely-extended shank or pin 31, the portion 32 thereof adjacent to the retainer proper 29 being of 70 angular or other shape in cross section to conform substantially to the shape and size of the hole 28. The end portion 33 of this shank is of cylindrical shape and of less cross section than the part 32, and at its 75 end is equipped or supplied with a retaining cotter-pin 34. Under normal conditions, the part 32 of this shank resides in the hole 28, the step or ledge 30 underlying the pin, as is shown in Fig. 3, the latter in turn preventing outward movement of the retainer because it lies in front of or overlaps the same. If the pin becomes broken, one or more parts thereof will fall or drop and rest on the ledge 30, the latter supporting 80 the same in operative position, and also acting by engagement with the pin as an indicator to show that the pin has been damaged or injured. In case this retainer is employed with the pivot-pin of a passenger 90 car, the pin would normally rest on the same, as has been explained above. To shift the retainer so as to bring it out of the path of the pin, the latter, after the cotter 18 has been removed, is forced upwardly 95 sufficiently so that no portion thereof lies in front of or overlaps the retainer, whereupon the latter may be moved into the dotted-line position shown in Fig. 3, bringing the smaller cylindrical part 33 of the shank into 100 the hole 28, and when the parts are in this position the retainer may be swung sideways away from the plane of the pin into the dotted-line position shown in Fig. 4, which will permit any fragments of a broken pin 105 to drop out of or be removed downwardly from the coupler.

A third modification or style of retainer is illustrated and shown in Figs. 5 and 6, and in this case the coupler 35 has cast on 110 its bottom a depending lug 36 supplied with a cylindrical hole 37 extended therethrough for the accommodation of the cylindrical shank 38 of a pivot-pin retainer 39, the latter being equipped with the customary step or ledge 40, while the shank 38 is supplied with an enlarged head 41 to prevent unintentional detachment of the retainer from the coupler. The top of the retainer 39 has a flat surface 42 which normally lies below, adjacent and parallel to the portion 43 of the coupler, the latter in advance of such shoulder 43 being recessed at 44. The retainer occupies ordinarily the full-line position shown in Fig. 5, the ledge or step 40 residing below the pivot-pin 12. Turning of the retainer and the shank 38 in the hole 37 is prevented under such circumstances by the coöperation of the surfaces 42 and 43. If, however, the pivot-pin is pushed 125 130

upwardly sufficiently so that it no longer lies in front of or overlaps the retainer, the latter may be slid outwardly, its shank 38 sliding in the hole 37, to the dotted-line position shown in Fig. 5, and may then be swung around, owing to the fact that the recess 44 permits turning of the main body of the retainer, into the dotted-line position of Fig. 6, in which position it is out of the plane of the pin. Otherwise, this particular style and form of retainer is provided for the same purpose and performs the same function as the other retainers set forth above.

15 I claim:

1. The combination of a coupler-head, a pivoted knuckle, a knuckle pivot-pin, and a pivot-pin retainer having a pin and hole connection with said coupler-head, said retainer pin being normally non-rotatable in its hole, thereby maintaining said retainer in operative relation with said pivot-pin, said retainer-pin being capable of rotation in its hole permitting shifting of the retainer into inoperative position when the pivot-pin is displaced longitudinally, substantially as described.

2. The combination of a coupler-head, a pivoted knuckle, a knuckle pivot-pin, and a pivot-pin retainer having sliding engagement with said coupler-head, said retainer being capable of turning during a portion of its sliding travel on said head to bring it into operative position with respect to said pivot-pin, said retainer being incapable of such turning and consequently being retained in operative position during the remainder of its sliding engagement, substantially as described.

3. The combination of a coupler-head, a pivoted knuckle, a knuckle pivot-pin, and a pivot-pin retainer having sliding engagement with said coupler-head and normally prevented from sliding by said knuckle pivot-pin, said retainer being capable of sliding when the pivot-pin is vertically dis-

placed and of turning during a portion of its sliding travel on said head to bring it into operative position with respect to said pivot-pin, said retainer being incapable of such turning and consequently being retained in operative position during the remainder of its sliding engagement, substantially as described.

4. The combination of a coupler-head provided with a hole therethrough, a pivoted knuckle, a knuckle pivot-pin, and a pivot-pin retainer having a shank pivoted and slideable in the hole in the said coupler-head, said shank having a portion angular in cross section and incapable of turning in said hole and another portion capable of such turning, whereby when the angular part is in such hole the retainer is maintained in operative relation with said pivot-pin and when the retainer is shifted to bring the other part of the shank into said hole the retainer may be turned into inoperative position, substantially as described.

5. The combination of a coupler-head provided with a hole therethrough, a pivoted knuckle, a knuckle pivot-pin, and a pivot-pin retainer having a shank fitted and slideable in the hole in said coupler head, said shank having a portion angular in cross section and incapable of turning in said hole and another portion capable of such turning, whereby when the angular part is in said hole the retainer is maintained in operative relation with said pivot-pin and when the retainer is shifted to bring the other part of the shank into said hole the retainer may be turned into inoperative position, said pivot-pin when in normal position preventing longitudinal movement of the shank of said retainer thereby preventing the retainer from being turned, substantially as described.
